UNITED STATES PATENT OFFICE.

RALPH O. NEWELL, OF VENUS, NEBRASKA.

WELL-AUGER.

SPECIFICATION forming part of Letters Patent No. 708,247, dated September 2, 1902.

Application filed December 1, 1899. Serial No. 738,939. (No model.)

To all whom it may concern:

Be it known that I, RALPH O. NEWELL, a citizen of the United States, residing at Venus, in the county of Knox and State of Nebraska, 5 have invented a new and useful Improvement in Earth-Augers, of which the following is a specification.

My invention relates to devices for drilling holes in earth; and it consists of means here- 10 inafter fully described, and specifically pointed out in the claims.

The annexed drawings and the following description set forth in detail certain mechanism embodying the invention, such dis- 15 closed means constituting but one of various mechanical forms in which the principle of the invention may be used.

In said annexed drawings, Figure I represents a cross-section of a device embodying 20 my improvement, taken upon the planes indicated by lines 1 1, Fig. II. Fig. II represents a plan view of such improvement.

A hollow cylindrical drum or auger-blade support A is provided with two oppositely- 25 located slots a, in which are respectively hinged the auger-blades B. Secured to the inside of said drum are two springs a', which respectively engage the blades B and urge or tend to urge same radially outward, so as 30 to project from the supporting - drum, as shown in Fig. II. Each blade is provided with a stop b, secured thereto, each consisting of an upwardly and a downwardly projecting member adapted to contact the inside of the 35 drum, limit the outward radial movement of the blades, and thereby determine the diameter of the hole or boring which may be formed with the auger. An auger-stem C is secured so as to be coaxial with the drum and 40 to project upwardly therefrom by means of angle-irons D, secured to the inner drum- surface and the lateral faces of the said stem. A double bracket E is secured to said stem and journals two pulleys e, one on each side 45 of said stem, respectively located adjacent to said slots a, as shown. The upper end of said stem is joined with the auger-rod F by means of a coupling consisting of a metal sleeve G, fixed to said rod by means of bolts g g. In 50 the lower end of said sleeve is transversely fixed a bolt g', passing into and through a slot c, elongated in the direction of the stem-

axis, thereby permitting said stem, drum, and blades to have a limited amount of axial or longitudinal movement upon said rod. Above 55 said sleeve and passing transversely through said rod F is a bolt f, projecting laterally from both sides of said rod, to which are attached the upper ends of two cords or chains H, which respectively pass around the pul- 60 leys e and have their other extremities secured to the auger-blades, as shown. The length of said cords or chains is made such that when the rod F is drawn upwardly, so as to cause the bolt g' to contact the upper end 65 of slot c, the blades will have been drawn inwardly, so as to substantially coincide with the auger-drum, as shown in dotted lines in Fig. II and to permit the said blades to assume their outermost position. (Shown in 70 full lines in said figure.)

In the operation of drilling into soil or earth the above-described construction of the device permits the rod F to assume its lowermost position, and thereby allow the 75 blades to assume their extreme outermost position. After a hole has been formed and it is desired to withdraw the auger the rod F is drawn upwardly, the first portion of its movement effecting no upward movement of 80 the auger. Such first movement, however, effects the inward or closing movement of the blades, which is followed by the upward withdrawal of the auger. Such construction and operation of the above-de- 85 scribed device permits the insertion of curbing into the hole formed having an outer diameter equal to or less than that of said hole, inasmuch as the auger may be raised or lowered inside such curbing while the blades 90 are in their closed position. Such closed position is maintained by the weight of the auger when suspended from rod F during such raising or lowering.

Other modes of applying the principle of 95 my invention may be employed instead of the one explained, change being made as regards the mechanism herein disclosed, provided the means stated by any one of the following claims or the equivalent of such 100 stated means be employed.

I therefore particularly point out and distinctly claim as my invention—

1. In an earth-auger, the combination of

an auger-drum, auger-blades supported upon and capable of radial movement relatively to said drum, springs connected with said blades and tending to give them outward radial movement, an auger-rod supporting said drum, the latter having a limited longitudinal movement upon said rod, and cords or chains connecting said rod and blades.

2. An earth-auger comprising the combination of a cylindrical drum having openings in its wall, auger-blades hinged in one end of said openings so as to swing outwardly, springs for effecting such outward

movement, each blade provided with a stop adapted to limit such movement, an auger-rod attached to said drum and movable relatively thereto, and cords or chains connecting said rods and blades, whereby said rod may be caused to actuate said blades to withdraw from their outward positions. 15 20

In testimony whereof I affix my signature in presence of two witnesses.

RALPH O. NEWELL.
